UNITED STATES PATENT OFFICE

117,619

DESIGN FOR A TEXTILE FABRIC

Joseph A. Krasnov, Philadelphia, Pa.

Application September 6, 1939, Serial No. 87,062

Term of patent 3½ years

To all whom it may concern:

Be it known that I, Joseph A. Krasnov, a citizen of the United States, residing at Philadelphia, in the county of Philadelphia and State of Pennsylvania, have invented a new, original, and ornamental Design for a Textile Fabric, of which the following is a specification, reference being had to the accompanying drawing, forming part thereof.

The figure represents a top plan view of a textile fabric embodying the design.

I claim:

The ornamental design for a textile fabric, substantially as shown.

JOSEPH A. KRASNOV.
